CHIMNEY SHADE FOR ELECTRICAL LAMPS

Howard Goodman, 63 E. 9th St., New York, N.Y.

Filed Oct. 12, 1961, Ser. No. 67,056

Term of patent 7 years

(Cl. D48—15)

FIG. 1 has a perspective view of a chimney shade for electrical lamps, showing my new design;

FIG. 2 is an enlarged sectional view taken on the lines 2—2 of FIG. 1; and

FIG. 3 is a bottom plan view of FIG. 1.

I claim:

The ornamental design for a chimney shade for electrical lamps, substantially as shown.
